B. P. HYDE

LOOSE POWDER VANITY BOX

Filed Feb. 20, 1925

Inventor:
Burdon P. Hyde
by his Atty's:
Henry George Rice Keeney

UNITED STATES PATENT OFFICE.

BURDON P. HYDE, OF WATERBURY, CONNECTICUT, ASSIGNOR TO SCOVILL MANUFACTURING COMPANY, OF WATERBURY, CONNECTICUT, A CORPORATION OF CONNECTICUT.

LOOSE-POWDER VANITY BOX.

Application filed February 20, 1925. Serial No. 10,467.

To all whom it may concern:

Be it known that I, BURDON P. HYDE, a citizen of the United States, residing at Waterbury, county of New Haven, and State 5 of Connecticut, have invented certain new and useful Improvements in Loose-Powder Vanity Boxes, fully described and represented in the following specification and the accompanying drawings, forming a part of 10 the same.

This invention relates to certain improvements in small boxes or cases for carrying cosmetics now commonly known as vanity cases, and particularly to a vanity case in 15 which the cosmetic is in the form of loose powder.

The especial object of the present invention is to provide a vanity box for loose powder which is constructed so as to be practically proof against accidental leakage of powder from the box, but in which access to the powder compartment is readily had by means of a lid or cover pivotally associated with the box so that it may be moved 25 out of the way while the powder is being used and will not interfere with the mirror or other article carried in the box.

A further object of the invention is to provide an improved hinge connection for 30 associating the cover of the powder compartment with the box, this hinge structure being combined with a puff holding device.

With these and other objects not specifically referred to in view, the invention consists in certain novel parts, arrangements and combinations which will be described in connection with the accompanying drawings and the novel features pointed out in the 35 claims hereunto annexed.

Referring now to these drawings,—

Figure 1 is a central vertical section of the improved box, the section being taken on line 1—1 of Fig. 2, the box being shown open;

Figure 2 is a plan view, partly broken away and partly in section, of the structure shown in Fig. 1;

Figure 3 is a section taken on line 3—3 of Fig. 2 in the direction of the arrow, and

Figure 4 is a plan view of a powder holding retainer used in the box.

Referring now to the drawings in detail, the box will include a body 1 and a cover 2 of any suitable or convenient size or shape,

the parts being pivotally associated by a 55 hinge 3. The body of the box is formed with a side wall or flange 4, and the cover is formed with a side wall or flange 5. The cover may also carry a reflecting surface, as a mirror 6, this being held in position by 60 a bezel 7.

In the particular box shown, the bottom is the powder container, and this container is provided with a lid, the lid and the container being so constructed that it is difficult for the powder to leak past the lid when the lid is closed, as shown in my prior Patent 65 No. 1,460,906. Like the construction shown in this patent, there is provided a powder retainer in the form of a member having a 70 vertical outer flange 8 which has a very tight frictional engagement with the walls of the box, and is further held in close engagement with the walls by nibs 9 in the box walls entering similar corresponding 75 indentations in the retainer. The retainer is formed with a top flat flange 10 which extends downwardly and angularly, as indicated at 11, and then vertically for a short distance, as indicated at 12. Cooperating 80 with this abutment is a lid, marked generally 13. This lid is provided with an angularly and inwardly extending flange 14 and a short vertical flange 15, the flange 15 and the flange 12 of the retainer having close 85 frictional engagement, as does the flange 14 and the angular surface 11 of the retainer, so that it is very difficult for powder to leak past these parts and escape from the 90 box. This construction is substantially the same as that shown in my prior patent. In the present box, however, the lid is mounted in a different way so that when the lid is open it will be out of the way of the mirror 95 or other reflecting surface carried in the cover of the box, and the lid is pivotally associated with the powder compartment, on a hinge of improved construction which is also provided with a part acting as a puff holder, so that a combined hinge or puff 100 holder is provided which lessens the number of parts, is more economical to construct, and one better adapted for certain uses than my prior box. As shown, the lid 13 is pivotally associated with the powder compartment 105 at a point away from the hinge 3, before referred to, so that the lid when in open position will be at a point to one side of the

- cover of the box and thus will not interfere with the use of the mirror. As is shown, the lid is pivoted at a point 90° away from the hinge 3.
- 5 This hinge lid may be of various constructions, but it will preferably be integral with a puff holder. As shown, the wall 8 and the flat flange 10 of the retainer, before referred to, are indented as shown at 10 16 in Figs. 2 and 4 to form a place for the hinge, so that the hinge is entirely within the box and does not show from the outer side thereof. As illustrated, the hinge comprises a vertical strap 17 secured to the wall 15 8 of the retainer, as by rivets 18, this strap being provided with hinge knuckles 19. The other strap 20 of the hinge is provided with knuckles 21, and the knuckles 19 and 21 are associated on a pin or pintle 22. These 20 knuckles are formed so as to lie closely adjacent to each other and form a rigid hinge construction.
- The strap 20 is extended inwardly over the flat flange 10, before referred to, and is 25 formed at its inner extremity with a resilient or spring puff holding tab or finger 23. In order that this puff holding tab or finger may properly effect its function and so that it will not be displaced to too great an extent by the insertion of a puff, the strap is 30 secured, as by rivets 24, to the cover or lid 13, the strap being bent inwardly and downwardly, as indicated at 25, to conform with the hollow, indicated at 26, formed in the 35 lid by the flange 14, before referred to.
- This depression in the lid forms a pocket or receptacle for a puff, indicated at 27, and in the best constructions the lid is unperforated throughout its extent, access to the 40 powder being obtained by lifting the lid.
- To facilitate the lifting of the lid, the flat flange 10, before referred to, is slightly hollowed out, as indicated at 28, so that a finger nail may be inserted under the flange 45 14 and the cover or lid readily lifted.
- In the best constructions, the cover 2 and the body 1 are provided with a spring catch, and such a catch is shown in Fig. 2, comprising a spring arm 29 secured to the inner wall of one of the parts, as the body 1, by a rivet 30, this arm having a wing 31 having a projection 32 over which snaps an indentation 33 formed in the cover 2. The 50 spring is released by a button 34 formed on the spring arm and extending through a suitable opening in the wall of the box. Where the spring catch is associated with the bottom of the box, it is located between the wall of the bottom and between the wall 55 8 of the retainer before referred to. To provide room for the operation of the catch, therefore, the wall of the retainer is indented, as indicated at 35, in Figs. 2 and 4.
- With the construction shown and described, a very neat, attractive and compact

loose powder box has been provided, one in which the powder is effectively prevented from accidentally escaping from the box, and one in which, due to the combination of the puff holder and hinge, less parts are needed 70 and a smaller and, therefore, less expensive structure is provided. While the invention is shown and described in its preferred form, it will be understood that various changes and arrangements may be made in 75 the detail structure for carrying out the invention. The invention, therefore, is not to be restricted to the exact details shown and described.

What I claim is:

1. In a loose powder vanity case, the combination of a body and a cover, one of these parts forming a powder compartment, a member in the powder compartment pivotally associated therewith on a hinge, and a 80 puff retaining member carried by the hinge and extending inwardly over a puff carried in the powder compartment.

2. In a loose powder vanity case, the combination of a body and a cover, one of these parts forming a powder compartment, a lid on the powder compartment dished for the reception of a puff, a hinge by which the lid is pivoted to the compartment, and a puff holder integral with the hinge and extending 90 over the lid.

3. In a loose powder vanity case, the combination of a body and a cover, one of these parts forming a powder compartment, a flanged member in the compartment, a lid 100 for the member, a hinge secured on the flange of the member, and a puff holder integral with the hinge extending inwardly over the lid and spaced from the surface thereof to provide space for a puff.

4. In a loose powder vanity case, the combination of a body and a cover associated on a hinge, one of these parts forming a powder compartment, a lid for the compartment, a hinge for the lid spaced from the hinge for the body and cover, and a puff holder carried by the hinge for the lid.

5. In a loose powder vanity case, the combination of a body and a cover associated on a hinge, the body forming a powder compartment, a mirror in the cover, a lid for the powder compartment, a hinge for the lid arranged on the compartment at one side of the hinge uniting the body and the cover, and a puff holder carried by the hinge for 115 the lid.

6. In a loose powder vanity case, the combination of a body and a cover, one of these parts forming a powder compartment, a lid on the powder compartment arranged for 125 the reception of a puff, a hinge by which the lid is pivoted to the powder compartment, a puff holder integral with the hinge and extending inwardly over a puff carried in the lid, and means for securing the puff 130

holder to the compartment between the end under which the puff is inserted and the hinge.

7. In a loose powder vanity case, the combination of a body and a cover associated on a hinge, the body forming a powder compartment, a mirror carried by the cover, a spring catch for securing the body and cover together,

a lid for the compartment, a hinge for the lid located between the spring catch and the hinge for the body and cover, and a puff holder carried by the hinge for the lid.

In testimony whereof, I have hereunto set my hand.

BURDON P. HYDE.
